(57) **CLAIM**

The ornamental design for a Christmas tree novelty, as shown and described herein.

DESCRIPTION

FIG. 1. Is a front view of my Christmas tree novelty with the dotted line showing being for illustrative purposes only and to which no claim is made;

FIG. 2. Is a rear view thereof, with the dotted line showing being for illustrative purposes only and to which no claim is made;

FIG. 3. Is a right side elevational view thereof, with the dotted line showing being for illustrative purposes only and to which no claim is made;

FIG. 4. Is a left side elevational view thereof, with the dotted line showing being for illustrative purposes only and to which no claim is made;

FIG. 5. Is a top view thereof, with the dotted line showing being for illustrative purposes only and to which no claim is made;

FIG. 6. Is a bottom view thereof, with the dotted line showing being for illustrative purposes only and to which no claim is made; and,

FIG. 7. Is an enlarged view showing in detail the fiber optic aspects of the design.
